WINDMILL PULLOUT

Edelbert John Knapp, Norton, Kans.

Application September 29, 1932
Serial No. 635,410

2 Claims. (Cl. 170—46)

My invention relates to windmill pullouts, its object being the provision of a pullout which is free from the defects found in similar pullouts now in use on windmills which are on the market.

5 An important object of the invention is the provision of a pullout which is entirely exposed on the outer side of the mast so that all parts of the pulicut are readily accessible.

Another object of the invention is the provision 10 of a novel swivel construction in the windmill pullout for preventing injury to parts of the pullout mechanism.

Another object of the invention is the provision 15 of a mast which is provided with a groove on its outer side for serving as a runway for the pullout chain without interfering with the turning of the windmill head on its vertical axis in the tower.

Another of my objects is the provision of a collar 20 surrounding the mast of the windmill and having a loose connection to permit the free rotation of the mast pipe therein, the rotation of the collar being limited so as to prevent kinking or twisting of the pullout wire.

Having in view these objects and others which 25 will be pointed out in the following description, I will now refer to the drawing, in which

Figure 1 is a view in elevation showing the upper part of a windmill tower and a portion 30 of the windmill head and showing particularly my novel form of pullout.

Figure 2 is a view in perspective of a portion 35 of the pullout mechanism in its relation to the mast, the view being drawn to an enlarged scale.

The windmill structure itself is of common construction as found in many windmills. The hood 40 10 encloses with the head 11 the working parts of the windmill. The wheel shaft 12 projects out through the head 11 and it is designed for supporting the wind wheel. The wheel shaft 12 is 45 journaled to the windmill head 11, its axis being shown at 14. The frame 13 supports the vane, the position of which determines whether the wind wheel shall be in or out of the wind. The shaft 12 and the frame 13 are positioned in alignment or substantially so when the wind wheel is 50 in the wind and these two parts are perpendicular to each other when the wind wheel is out of the wind. As thus far described the details are found in numerous windmills and they are of 55 such common knowledge that further description is believed to be unnecessary.

The action of the windmill is stopped by turning the vane frame 13 on its axis 14 until the frame 13 assumes a position substantially at right angles to the shaft 12. For convenience the con-

trol is positioned in the lower portion of the tower so that it will be accessible at all times to the user of the windmill without necessitating his climbing to the top of the tower. The control is known as a pullout and the art discloses numerous variations. It is my object to not only simplify the pullout but to make it more reliable in action and to make it more readily accessible for repairs.

The windmill head is swiveled about a vertical axis on a tower which usually consists of four 60 posts 15, the tower having a casting 16 for holding the posts 15 together at their upper extremities and for supporting the head 11 with the working parts of the windmill. The mast pipe 17 is rigid with the head 11 and it depends therefrom. It consists of an upper and a lower part 65 joined together, the upper part receiving the lower part in telescoping relation and providing a shoulder which rests on the casting 16. The mast pipe is provided at its lower end with a guide in 70 the form of a spider 18 which is secured to all four of the tower posts 15. The spider 18 prevents the rocking of the mast pipe 17.

The pullout chain 19 is secured to the vane frame 13 and it then passes around a pulley 20 80 and then another pulley 21, terminating in an S-link 22 which is connected to an L-shaped link 23, the L-shaped link 23 being in turn secured to a collar 24 surrounding the mast pipe 17. The collar 24 is free to slide up and down on the mast 85 pipe 17 but it is prevented from freely rotating thereon. The mast pipe is provided throughout the major portion of its length with a groove 25 which is formed in its outer wall. The groove 25 is deep enough to seat the chain 19 so that the 90 mast pipe 17 is free to rotate in the casting 16 without interfering with the chain 19.

Surrounding the collar 24 are two clamping members 26 which loosely engage the collar 24. The clamp 26 is free to rotate about the collar 95 24 and it serves as a support for the elongated U-shaped link 27. The clamp 26 is provided with an arm 28 which is sufficiently long to pass between two of the posts of the tower. This is done in order to limit the rotation of the clamp 26 due 100 to its friction with the collar 24. The rotation of the clamp 26 is thus limited to the arc determined by the distance between two posts of the tower. The device is completed by attaching a wire 29 to the lower loop of the link 27 and then 105 fastening the wire at its lower extremity to the pullout lever found at the lower portion of every windmill tower.

Having thus described my invention in such full, clear, and exact terms that its construction 110

and operation will be readily understood by others skilled in the art to which it pertains, what I claim as new and desire to secure by Letters Patent of the United States is:

- 5 1. A windmill including a tower, a head having a tubular mast swiveled in said tower, a vane frame secured to said head through a vertical hinge, a pulley journaled to said head, said tubular mast being provided with a vertical groove on the outer side thereof, a collar slidably surrounding said mast, a flexible member trained over said pulley and secured at its extremities to said vane frame and to said collar respectively, said flexible member being seated in the groove in said mast, and means for sliding said collar on said mast, said collar being held against rotation on said tubular mast by said flexible member.
- 10
- 15

2. A windmill including a tower and a head, a tubular mast depending from said head and journaled in said tower, said mast being provided with a vertical groove on the outer side thereof, a 80
slidable member seated within the groove of said mast and passing through the bearing of said mast in said tower, a collar slidably secured to said mast about the lower portion thereof, said slidable member being secured to the under side of said collar, means for limiting the rotation of 85
said collar about said mast for preventing the twisting of said slidable member, a U-shaped member depending from said collar, and a manually operable pullout wire depending from said U-shaped member.
